UNITED STATES PATENT OFFICE.

JOHN MILTON BENJAMIN, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

MACHINE FOR SEPARATING LASTS AND SHOES.

1,299,816.

Specification of Letters Patent.

Patented Apr. 8, 1919.

Application filed February 17, 1917. Serial No. 149,336.

To all whom it may concern:

Be it known that I, JOHN M. BENJAMIN, a citizen of the United States, residing at Beverly, in the county of Essex and State of Massachusetts, have invented certain Improvements in Machines for Separating Lasts and Shoes, of which the following description, in connection with the accompanying drawings, is a specification, like reference characters on the drawings indicating like parts in the several figures.

This invention relates to machines for separating lasts and shoes and more particularly to machines of the general type illustrated in United States Letters Patent No. 1,203,571, granted November 7, 1916, upon my application, Serial No. 13,385, filed March 10, 1915, in which the shoe is held while the last is pulled therefrom by a pulling mechanism constructed and arranged automatically to conform its line of pull to effect separation with minimum resistance from the shoe operated upon, and consequently with minimum strain upon the shoe parts.

In machines of this type, the last with its shoe is mounted upon a holding member or support which is moved by the operator to position the shoe in coöperative relation to certain shoe gripping instrumentalities, a clutch treadle being subsequently operated to start the power-operated cycle of the machine which closes the gripping means upon the positioned shoe and causes the pulling mechanism to operate to extract the last from the gripped shoe. Obviously, an interval of time elapses between the positioning of the shoe and the starting of the machine, and the aggregate of these intervals in a day's work represents a substantial amount of time lost. Elimination of this time wastage by causing the mechanism of the machine to be started responsively to movement of the shoe to a position of coöperation with the gripping instrumentalities substantially increases the output of the machine.

Accordingly, a feature of the invention consists in operatively connecting the starting mechanism with the last and shoe support or holder in such manner that the

starting mechanism is operated in response to movement of said support or holder to the position in which the supported shoe is in coöperative relation to the shoe gripping instrumentalities.

An increasing number of hinge lasts are being used in the manufacture of shoes and, since this type of last is more readily extracted from the shoe when the locking means for its hinge is released or the last broken than the solid or non-hinged type, an arrangement and combination of parts which automatically "breaks" the hinges of hinge-type lasts, when the last with its shoe is presented to the shoe gripping means in the ordinary operation of the machine, represents a substantial contribution to the rapid and successful operation of the machine.

To this end, therefore, a further feature of the invention consists in means arranged to break the hinges of hinged lasts upon which shoes have been lasted and which come to the machine to have the lasts extracted from the shoes. As herein shown, and as a further feature of the invention, said means are arranged to break the hinges automatically upon the presentation of the last and shoe support to the gripping means for the shoe.

In machines of the described type, the last pulling mechanism exerts a constant lengthwise pull on the last in the direction of the heel of the shoe while at the same time pulling the last downwardly in a direction substantially perpendicular to the plane of the last bottom to clear the edge of the shoe counter. Until the last heel has cleared the shoe counter the heel end of the shoe opposes lengthwise heelward movement of the last and there is no appreciable lengthwise heelward component of movement on the part of the last. A spring in the pulling mechanism causes said mechanism yieldingly to pull the heel end of the last downwardly during the first part of the pulling operation so as to prevent injury to the shoe parts during the crucial stage of separation, the compression of the spring during this period increasing the normal tendency of the last to

move lengthwise heelward and storing up power effective to accelerate lengthwise heelward movement of the last when the last heel clears the shoe counter.

5 The spring means providing this increased tendency for lengthwise heelward last movement in machines constructed in accordance with said prior application and patent, has proved generally satisfactory in use. In a 10 few instances, however, this lengthwise thrust has been of sufficient force to injure the back seams of shoes, particularly shoes of light construction. In order to make the machine better adapted for all classes of 15 work while retaining the advantages of said prior construction I have provided means for reducing the normal lengthwise thrust of the last heel against the shoe counter during the period of relative vertical movement 20 of the last heel and shoe counter to clear each other.

Accordingly, another feature of my invention consists in means auxiliary to the last and shoe separating mechanism which is effective to reduce normal lengthwise relative thrust of the last heel and shoe counter during said period. In the illustrated machine, a spring acting against the bell crank lever to which the last carrier is attached, is arranged to yield independently of movement of the last pulling plunger and responsive to resistance offered by the shoe counter to lengthwise thrust of the last heel and thereby to reduce said lengthwise thrust while the last heel is moving to clear the shoe counter. After the bottom of the last heel has cleared the top of the shoe counter, this spring is effective through compression to accelerate the lengthwise heelward movement of the 40 last.

A further feature of the present invention consists in means, auxiliary to the last and shoe separating mechanism, coöperating with said mechanism and exerting force tending to increase the force of the normal relative lengthwise separating movement of the shoe and last after the last heel and shoe counter have cleared each other, with means to vary the force so exerted to suit the requirements for high and low shoes. With high shoes, stronger backward, or lengthwise heelward, pull is required than with low shoes or oxfords, since the last must be pulled lengthwise with sufficient force to overcome 55 the resistance offered by the back stays of the tops of high shoes. In the illustrative embodiment, two concentric springs are employed, these springs being arranged to be compressed by the pulling of the last during 60 the crucial stage of the operation as described and coöperating with the pulling mechanism to increase the force of the lengthwise component of pulling movement after the last heel has cleared the shoe coun-

ter. One of these springs will represent a 65 force suitable for low shoe work and the other spring an added force sufficient to meet the extra demand for high shoe work. This last spring is arranged quickly to be rendered inoperative and to be again restored to operative condition so that the operator can change the spring power in an instant.

As previously practised, the heel extremity of the shoe has been positioned against a back stop and the shoe gripped and held by gripping means operating against opposite sides of the shoe counter. In the illustrative embodiment of the invention, I have shown counter and heel gripping blocks and shank supporting fingers such as shown in the prior 80 patent, previously referred to. In the use of these gripping devices it has been found that in operating on shoes having thin upper stock, there is a tendency to wrinkle the upper leather at the counter, particularly if it 85 is not glued to the counter, owing to the tendency of the shoe very slightly to turn relatively to its grippers during the extraction of the last.

A further feature of the invention consists in means providing a back stop and support for the counter of the shoe which may be used without counter, heel or shank grippers, the operator holding the forepart of the shoe against the back stop and support and approximately in a horizontal plane, or which may be used in combination with the counter, heel and shank supports, or any of them and which will prevent turning of the shoe and wrinkling of the upper 100 under the described and similar conditions. This back stop and counter support is in the form of a suitably supported backing member to which is attached a pad or block of relatively soft resilient material, preferably rubber, having in its face a concave recess curving outwardly to the face of the block at its base to form a lateral support for the upper end of the counter and contoured both vertically and horizontally to 110 conform approximately to the corresponding contours of the heel end of a shoe.

Since the counter is embraced at opposite sides of its longitudinal median line and the undercut curve at the top of the counter 115 receives lateral support, (the last and shoe being in inverted position), any slight tendency of the extremity of the shoe to turn downwardly under last pulling tension is taken up by the compression of the elastic 120 cushion forming the back stop and counter support so that there is no such relative rubbing movement between the shoe counter and its support as to cause the formation of wrinkles in the thinnest upper stock.

These and other features, including certain novel constructions, will be more fully apparent from the following detailed speci-

fication when read in connection with the accompanying drawings in which:

Figure 1 is a view in side elevation of a last pulling machine of the described type embodying the features of the present invention;

Fig. 2 is a fragmentary perspective view of the gripping head, last holder and associated parts;

10 Fig. 3 is a perspective view of the back stop and counter support, and

Fig. 4 is a detail of the spring tension control.

Machines of the illustrated type embody 15 an upright hollow column 2 in the upper portion of which is journaled a shaft rotated by power from a continuously rotating power driven pulley 6 loose upon the shaft 4 and transmitting power to the shaft 20 through a suitable clutch of the one cycle type operated to connect the shaft and pulley by a suitable actuating lever such as the starting treadle 8. Motion is transmitted from shaft 4 to a cam shaft 10 by reducing 25 gearing. A cam on the cam shaft operates through a bell crank lever 12, cross-head 14 and suitable connections coincidently and yieldingly to move counter grippers 16, heel grippers 18 and shank grippers 20 into gripping engagement with the opposite sides of 30 the shoe. Subsequently certain cams become effective to depress a thrust bar 22, swinging downwardly the forward end of a lever 24 connected to the lower end of a plunger 26 35 and effective to move said plunger downwardly.

Downward movement of this plunger is arranged to effect the separation of the last from the shoe. A bell crank lever is pivotally mounted on the upper end of this plunger, its upper arm 28 having the rear end of 40 a last carrier or holder 30 pivotally secured to its upper end. This carrier intermediate of its ends, is provided with an upstanding last pin 32 to engage in the last thimble of 45 the last, and has its forward end formed to serve as a handle by which the operator may swing the carrier upwardly to position the last-carried shoe in coöperative relation 50 to the back stop and gripping means.

The lower arm 34 of the bell crank lever has pivotally attached to its forward end, the upper end of a rod 36 upon which, at a point below arm 34, a spring housing sleeve 55 38 is adjustably secured. The lower end of this rod extends freely through a bore in the forward end of a bracket 40 secured at its rear end to the lower end of plunger 26 and moving with said plunger. Between 60 the upper face of the bracket and the sleeve 38 a coiled spring 42 is sleeved on rod 36, this spring being compressed by downward movement of bell crank arm 34 responsive to resistance offered by the shoe counter to

lengthwise thrust of the last during the 65 first part of the pulling operation so that as soon as the last heel clears the shoe counter, the tension of the spring acts against the bell crank lever to accelerate the lengthwise rearward movement of the last. 70

My invention contemplates the provision of additional spring means which may be readily placed in operative or inoperative condition and which, when operatively conditioned, will coöperate with the bell crank 75 lever similarly to spring 42 further to increase the force of lengthwise rearward movement after the last heel has cleared the top of the shoe counter. This increase is desired, as previously stated, to overcome 80 the additional resistance offered by the back stays of high shoes. Accordingly, a coiled spring 44 of less diameter than the spring 42 and concentric therewith is sleeved upon the rod 36 with its upper end engaging the 85 housing sleeve 38 and with its lower end abutting a washer 46 mounted upon the rod 36 and freely movable through a bore in bracket 40, means being provided as later described to detachably anchor this spring 90 and washer to the bracket so that the rod may slide therethrough. The bore in this bracket is increased in diameter below the top of the bracket to receive a locking sleeve 48 sliding freely on rod 36 and having a 95 bayonet slot 50 in its upper edge arranged to coöperate with a pin 52 extending inwardly from the bracket 40 to a point to coöperate with the bayonet slot without extending within the line of movement of the washer 100 46. Obviously, the sleeve 48 is of a substantially larger diameter than the washer 46, and since both the washer and sleeve are bored to slide upon the rod 36, the sleeve 48, when turned to release the pin 52, 105 may slide to the lower end of rod 36 and engage the head 54 of the rod, the washer 46 and sleeve 48 being forced downwardly by the spring 44 until the sleeve abuts the top face of the head 54 as shown 110 in Fig. 1. The coiled spring 44 will thereby be distended, its length being figured to be such that when the locking sleeve is released, the distension of the spring 44 will prevent any appreciable pressure of the 115 spring against the arm 34 of the bell crank lever. Obviously, downward movement of the arm 34 during the first part of the last pulling operation will not act against spring 44, since this spring will move downwardly 120 with the rod 36 and is no longer anchored relatively to the bracket 40. To restore the spring 44 to operative condition, it is only necessary to move the sleeve 48 and washer 46 upwardly to insert the pin 52 in the 125 bayonet slot 50 and to turn the sleeve to lock it and the washer 46 in spring tensioning position. In this position of the spring

44 it will be obvious that when arm 34 of the bell crank is moved downwardly during the pulling of the last, spring 42 and spring 44 will both be compressed and their combined tension will be effective against the bell crank lever to move the last lengthwise rearwardly of the shoe when the last heel clears the shoe counter.

At the base of the column 2 above the 10 aligned portion of the treadle 8, a bracket 56 is attached to the column. Pivoted to the forward end of the bracket at a point intermediate of its ends is a lever 58, the forward end of the lever having attached thereto the upper end of a depending link 60 whose lower end is pivoted to the clutch-actuating lever 8. Since it may be necessary, as in making adjustments, to operate the clutch independently of the last pulling 20 operation the lever 8 may be advantageously formed as a foot lever or treadle. A chain or similar connection 62 is attached to the rear end of the lever 58 and to the last carrier 30 adjacent to its forward end and is of such length that when the last carrier 30 is swung upwardly by the operator a sufficient distance to position the shoe on the last in coöperative relation to the back stop and shoe gripping blocks and fingers, the 30 lever 58 and link 60 will be moved sufficiently to operate the treadle 80 to start the power operated cycle of the machine.

A bracket 64 is adjustably mounted upon the head of the machine rearwardly of the 35 gripping members, and extends forwardly over the position occupied by the shoe. At a point rearwardly of the heel end of the shoe it is formed with a flat-sided vertical bore, through which a stem 66 extends downwardly to a point in line with the heel end 40 of the shoe position and is provided with a backing plate 68 to which a back stop and counter supporting block 70 are attached. The rod 66 with its backing plate and block 45 70 is adjustably supported from the bracket by means of a set screw 72.

Forwardly of the rod 66 and at a point in line with the heel of the positioned shoe, the bracket is formed with a second flat 50 sided bore, through which a rod 74 extends downwardly and is provided at its base with a heel gage plate 76, adjustably supported by the set screw 78, the top face of the heel of the shoe engaging the plate 76 when 55 the shoe is positioned in coöperative relation to the back stop 70 and to the counter and heel grippers 16 and 18.

Forwardly of this point the bracket is 60 curved upwardly and terminates in a split clamping sleeve 80, similarly having a flat-sided bore therein to prevent turning of the horizontal rod 82 clamped in the sleeve, the forward end of this rod terminating at a point above the forepart of the sole of a positioned shoe and having fixedly attached

thereto a split clamping member 84, having a vertical bore therein. The upper end of a vertical rod 86 is clamped in this bore. Its lower end is provided with a bearing bracket 88 between the bifurcated arms of which a 70 roller 90 is journaled. This roller is positioned with its lower edge at an elevation to place the sole of the shoe in the proper plane relatively to the gripping instrumentalities when the sole of the shoe is in contact with 75 the roller.

The roller 90 is intended forcibly to engage the sole of a shoe which has been made over a hinged last to break the lock of the hinge of the last as previously described. 80 Accordingly, when the operator mounts a hinged last with its shoe on the last pin 32 of the last carrier 30 and swings the last carrier upwardly to position the shoe in coöperative relation to the heel gage plate, 85 back stop and the gripping instrumentalities, he brings the sole of a supported shoe against the roller 90 with sufficient force to break the lock of the hinge joint of the last so that the last is in condition readily to be pulled from 90 the shoe when the latter is gripped. It will be seen, therefore, that instead of having to break the lock of the hinge joint of the last before mounting the last on the carrier, the operator merely mounts the last upon the 95 carrier in the usual manner and swings it smartly upwardly, properly positioning the shoe, breaking the lock of the hinge joint of the last and automatically starting the power operated cycle of the machine at one and the 100 same time.

The block 70 is of relatively soft, resilient material, such as soft rubber, and has its outer face formed with a concave recess 92 extending from a point adjacent to the lower edge of the block upwardly to the upper edge of the block, forming at its lower end an outwardly and laterally inclined seat 94 to accommodate the inward curvature of the upper end of the counter at the extreme end 110 of the heel and supporting the counter against vertically downward movement. Preferably, the concaved portion of the block adjacent to its upper end is undercut, as at 96, to receive the head of a suitable 115 member for securing the block to the backing plate 68 with this head out of the plane of the recess to obviate any contact with the counter of the shoe. Preferably, the rear face of the block 70 is formed with a suitable seat for the edges of the backing plate 120 to insure rigid support for the block.

When the last is pulled from the shoe, the downward and rearward direction of the pulling force has a tendency to cause the 125 shoe slightly to turn relatively to its gripping means and slightly to move its heel end downwardly relatively to the back stop. As previously stated, this tendency has resulted, with previous constructions, in permit- 130

ting slight relative movement between the back stop and the counter with the result that if the upper is not glued to the counter, thin upper stock may wrinkle. The outwardly inclining supporting surface 94 of the block 70 supports the counter against any appreciable downward movement, the soft resilient material permitting compression of the material by the exerted force without causing relative movement between the back stop and upper material to wrinkle the upper. In fact, the support afforded by the back stop and counter supporting block 70 is of such positive character that the counter and heel gripping blocks, and the shank supporting fingers illustrated herein, may be omitted and the forepart of the shoe may be grasped and supported by the hand of the operator. Obviously, however, the back stop and counter supporting block 70 may be used in combination with the counter, or heel grippers, or both, and also with the shank supporting fingers, if desired.

While the various features of the invention have been illustrated and described in connection with a specific type of mechanism, they are not limited to use in the combination with the specific structures disclosed or to the particular type of machine, except as specifically stated in the appended claims.

Having described my invention, what I claim as new and desire to secure by Letters Patent of the United States is:

1. In a machine for separating lasts and shoes, in combination, last holding means and shoe holding means relatively movable to position the shoe on a supported last and said shoe holding means in coöperative relation, power operated mechanism for effecting relative movement between the last holding and shoe holding means to separate the last and shoe, starting means for said mechanism, and means to operate said starting means by relative movement of the last holding and shoe holding means to coöperative relation.

2. In a machine for separating lasts and shoes, in combination, shoe holding means, last holding means movable to position the shoe on a supported last in coöperative relation to said shoe holding means, power operated mechanism for effecting relative movement between the shoe holding and last holding means to separate the last and shoe, and starting means for said mechanism responsive to the movement of the last holding means into operative position.

3. In a machine for separating lasts and shoes, in combination, last holding means and shoe gripping means relatively movable to position the shoe on a supported last and said gripping means in coöperative relation, power operated mechanism for causing the gripping means to grip and hold the positioned shoe and for subsequently effecting

relative movement between the last holding and shoe gripping means to separate the last and shoe, starting means for said mechanism, and means to operate said starting means by relative movement of the last holding and shoe gripping means to coöperative gripping relation.

4. In a machine for separating lasts and shoes, in combination, shoe gripping means, last holding means manually movable to position the shoe on a supported last in coöperative relation to said gripping means, power operated mechanism to operate the gripping means to engage and hold the positioned shoe and subsequently relatively to move the last holding and shoe gripping means to separate the last and shoe, starting means for said mechanism, and operative connections between said starting means and last holding means constructed and arranged to actuate the starting means by manually effected movement of the last holding means to position the shoe in coöperative relation to the shoe gripping means.

5. In a machine for separating lasts and shoes, in combination, shoe holding means, last holding means manually movable to position the shoe on a supported last in coöperative relation to the shoe holding means, power operated mechanism for effecting movement of the last holding means to pull the last from the shoe in directions substantially perpendicular to the plane of the shoe bottom and lengthwise heelward of the shoe, starting means for said mechanism, and connections between said starting means and the last holding means constructed and arranged to actuate the starting means by manually effected movement of the last holding means to position the shoe into coöperative relation to the shoe holding means.

6. In a machine for separating lasts and shoes, in combination, shoe gripping means, last holding means manually movable to position the shoe on a supported last in coöperative relation to said gripping means, power operated mechanism to operate the gripping means to engage and hold the positioned shoe and subsequently to move the last holding means in a direction to pull the last from the shoe in directions substantially perpendicular to the plane of the last bottom until the last heel clears the shoe counter and thence lengthwise heelward of the shoe, starting means for said mechanism, and operative connections between the starting means and last holding means effective to actuate said starting means by the manually effected movement of the last holding means to a position in which the supported shoe is in coöperative relation to the shoe gripping means.

7. In a machine for separating lasts and shoes, in combination, shoe gripping means, a pulling member, a last holder operatively

- connected therewith and mounted for manually effected movement relatively to the pulling member and shoe gripping means to position the supported shoe in coöperative relation to said gripping means, power operated mechanism effective to move said pulling member and last holder in directions to pull the last from the shoe, starting means for said mechanism including an actuating lever, and operative connections from said lever to said last holder effective to actuate said lever and the starting means by the manually effected movement of the last holder to a position in which the supported shoe is in coöperative relation to the shoe gripping means.
8. In a machine for separating lasts and shoes, in combination, last holding means and shoe holding means relatively movable to position the shoe in a supported last in coöperative relation to the shoe holding means, power operated mechanism for effecting relative movement between the last holding means and shoe holding means to separate the last and shoe, a one-cycle clutch for said power mechanism including a starting lever, and means operated by said relative shoe positioning movement of the last holding and shoe holding means to operate said lever and start the power operated cycle of the machine.
9. In a machine for separating lasts and shoes, in combination, shoe holding means, last holding means movable to position the shoe on a hinged last in coöperative relation to the shoe holding means, means for breaking the hinged last, and mechanism for effecting relative movement between the last holding means and the shoe holding means to separate the last and shoe.
10. In a machine for separating lasts and shoes, in combination, shoe gripping means, last holding means movable to position the shoe on a hinged last in coöperative gripping relation to the shoe gripping means, an abutment member positioned in the line of last movement to be engaged by the forepart of the shoe to break the last, and mechanism for causing said gripping means to engage and hold the positioned shoe and for subsequently effecting relative movement between the last holding and shoe gripping means to separate the last and shoe.
11. In a machine for separating hinged lasts and shoes in combination, shoe gripping means, a last holding member manually movable to position the shoe on a supported last in coöperative gripping relation to said gripping means, an abutment member positioned to engage the bottom of the forepart of a shoe so positioned, and mechanism to close the gripping means upon the positioned shoe to hold the shoe, and relatively to move the shoe gripping means and last holding means to separate the shoe and last.
12. In a machine for separating hinged lasts and shoes, in combination, shoe holding means, a last holding member manually movable to position the shoe on a supported last in coöperative relation to said shoe holding means, an abutment member positioned to engage the bottom of the forepart of a shoe so positioned, and mechanism operable to move the last holding member to pull the last from the shoe.
13. In a machine for separating shoes and lasts, in combination, last holding means, shoe holding means, mechanism for effecting relative movement of the last holding means and the shoe holding means to separate the last and shoe including relative movement of the shoe and last holding means lengthwise of the last and shoe after the shoe counter and last heel clear each other, multiple spring means constructed and arranged to coöperate with said mechanism to exert additional force in said lengthwise separating movement and means inoperatively to condition one of said spring means to vary the amount of said additional force.
14. In a machine for separating lasts from shoes, in combination, shoe holding means and last holding means relatively movable to position a supported shoe in coöperative relation to the shoe holding means, mechanism operable to effect movement of the last holding means to separate the last from the shoe including lengthwise heelward movement of the last holding means after the last heel clears the shoe counter, and auxiliary means constructed and arranged to coöperate with said mechanism additionally to force the last holding means lengthwise heelward and including a plurality of power units operative conjointly to provide maximum additional force to overcome the resistance of the tops of high shoes to such lengthwise heelward last movement and means inoperatively to condition one of said power units.
15. In a machine for separating lasts from shoes, in combination, shoe holding means and last holding means relatively movable to position a supported shoe in coöperative relation to the shoe holding means, mechanism operable to effect movement of the last holding means to pull the last from the shoe in a direction substantially perpendicular to the plane of the last bottom until the last heel clears the shoe counter and then lengthwise heelward of the shoe, and auxiliary means constructed and arranged to coöperate with said mechanism additionally to force the last lengthwise heelward and including a plurality of springs arranged conjointly to be compressed by the movement of the last holding means to clear the last.

- heel from the shoe counter and subsequently effective to accelerate the lengthwise last movement and means inoperatively to condition one of said springs for compression.
- 5 16. In a machine for separating lasts from shoes, a last holder, a supporting member for said holder pivoted for swinging movement, a plurality of springs constructed and arranged to act against said supporting member to swing said holder, and means inoperatively to condition one of said springs.
- 10 17. In a machine for separating lasts from shoes, a last holder, and means to operate said last holder to pull a last from a shoe, including a plunger, a bell crank lever fulcrumed on the plunger, a last holder pivoted to one arm of said bell crank lever, a plurality of springs constructed and arranged to act against the other arm of the bell crank lever to swing said first mentioned arm and the connected last holder in a direction lengthwise of a supported last and means for inoperatively conditioning one of said plurality of springs.
- 15 18. In a machine for separating lasts from shoes, in combination, a plunger, a bell crank lever fulcrumed on the plunger, a last holder pivoted to one arm of the bell crank lever, an abutment below said bell crank lever, a rod pivoted to the other arm of said bell crank lever and guided through said abutment, a plurality of springs sleeved on said rod and interposed between said bell crank arm and said abutment, and means to
- 20 release one of said springs from compressive engagement with said abutment.
- 25 19. In a machine for separating lasts from shoes, in combination, means for holding a last, means for holding a shoe comprising a support of compressible material having a concave recess therein curved to receive the portion of the counter at the extremity of the shoe and to support the lower edge of said extremity of the counter against depression, and mechanism for effecting movement of the last holding means to separate the last from the shoe.
- 30 20. In a machine for separating lasts from shoes, in combination, a back stop and support for shoes fixedly positioned and including a block or pad of compressible material having a concave recess therein curved to receive the counter portion at the extremity of a shoe and to support the lower edge of said extremity of the counter against depression, a last holder arranged for manually effected movement to position the extremity of the counter in coöperative relation to said recess in the back stop and support, and mechanism for effecting movement of the last holder in a direction to pull the last from the shoe.
- 35 21. In a machine for separating lasts from shoes, last holding means, a back stop and counter support for shoes comprising a block
- 40 of compressible material rigidly supported and having its face concaved to conform approximately to the transverse and vertical curvature of the counter portion of a shoe at its extremity, said concave face at its lower end providing an outwardly and laterally curved seat to accommodate and to support against depression the lower edge of the counter portion engaging the back stop, and mechanism for moving the last holding means in a direction to remove the last from a shoe engaging said counter support.
- 45 22. In a machine of the class described, the combination with last holding means, shoe holding means and mechanism for effecting relative movement of said holding means to effect relative separating movement of the shoe and last including relative lengthwise movement, of auxiliary means coöoperating with said mechanism constructed and arranged to reduce the normal relative lengthwise thrust of the last heel and shoe counter during relative vertical movement of the last heel and shoe counter to clear each other.
- 50 23. In a machine of the class described, the combination with last holding means, shoe holding means and mechanism for effecting relative movement of said holding means to effect relative separating movement of the last and shoe producing relative lengthwise thrust of the last heel and shoe counter, of auxiliary spring means co-operating with said mechanism constructed and arranged to yield responsively to resistance offered by the shoe counter to said lengthwise thrust to reduce the normal relative lengthwise thrust of the last heel and shoe counter during the relative vertical movement of the last heel and shoe counter to clear each other.
- 55 24. In a machine of the class described, the combination with last holding means, shoe holding means and mechanism for effecting relative movement of said holding means to effect relative separating movement of the last and shoe producing relative lengthwise thrust of the last heel and shoe counter, of auxiliary spring means coöoperating with said mechanism constructed and arranged to yield responsively to resistance offered by the shoe counter to said lengthwise thrust to reduce the normal relative lengthwise thrust of the last heel and shoe counter during the relative vertical movement of the last heel and shoe counter to clear each other, said spring means acting through compression by resistance offered to said thrust to accelerate relative lengthwise movement of the last and shoe after the last heel and shoe counter clear each other.
- 60 25. In a machine of the class described, the combination with shoe gripping means, last holding means and mechanism for mov-

ing the last holding means to remove a last from its shoe with a lengthwise component of movement producing lengthwise thrust of the last heel against the shoe counter, 5 of auxiliary means coöperating with said mechanism constructed and arranged to reduce said lengthwise thrust of the last holding means and last responsively to resistance offered to said lengthwise thrust by the 10 counter portion of the shoe.

26. In a machine of the class described, the combination with shoe gripping means, last holding means and mechanism for moving the last holding means to remove a last 15 from its shoe with a lengthwise component of movement producing lengthwise heelward thrust of the last heel against the shoe counter, of auxiliary spring means coöperating with said last holding means and with 20 said mechanism constructed and arranged to cause the last holding means and last to yield lengthwise responsively to resistance offered by the shoe counter to lengthwise thrust of the last to reduce the normal 25 lengthwise thrust of the last heel against the shoe counter.

27. In a machine of the class described, the combination with shoe gripping means, last holding means and mechanism for moving the last holding means to remove a last 30 from its shoe with a lengthwise component of movement producing lengthwise heelward thrust of the last heel against the shoe counter, of auxiliary spring means coöperating with said last holding means and with 35 said mechanism constructed and arranged to cause the last holding means and last to yield lengthwise responsively to resistance offered by the shoe counter to lengthwise 40 thrust of the last to reduce the normal lengthwise thrust of the last heel against the shoe counter, said spring means acting through compression by said resistance offered by the

shoe counter to accelerate lengthwise movement of the last holding means and last after 45 the last heel has been moved vertically to clear the top edge of the shoe counter.

28. In a last pulling machine, shoe gripping means and last removing means comprising a plunger, a bell crank lever fulcrumed on the plunger, a last carrier connected to one arm of said lever and a spring acting against the other arm of said lever mounted to yield independently of movement of said plunger and responsively to 55 swinging movement of said lever in one direction.

29. In a last pulling machine, shoe gripping means, and last removing means comprising a plunger, a bell crank lever fulcrumed on the plunger, a last carrier connected to one arm of said lever, a spring support carried by and moving with said plunger and a spring interposed between 60 said support and the other arm of said lever and yieldingly opposing swinging movement of 65 said lever in one direction.

30. In a last pulling machine, means for gripping the counter portion of a shoe, and last removing means comprising a plunger 70 positioned rearwardly of said counter gripping means and movable in a plane substantially perpendicular to the bottom of a gripped shoe, a bell crank lever fulcrumed on said plunger, a last carrier connected to 75 one arm of said lever, a bracket carried by and moving with said plunger, a rod guided in said bracket and connected to the other arm of said lever, and a coiled spring acting against said lever arm sleeved on said rod 80 between said bracket and said lever arm and yieldingly opposing swinging movement of said lever in one direction.

In testimony whereof I have signed my name to this specification.

JOHN MILTON BENJAMIN.
